UNITED STATES PATENT OFFICE.

RALPH DEANE SHURE, OF CLARENDON, TEXAS.

CLOCK-ACTUATED DISPLAY APPARATUS.

1,247,589.

Specification of Letters Patent. Patented Nov. 20, 1917.

Application filed January 3, 1917. Serial No. 140,419.

To all whom it may concern:

Be it known that I, RALPH DEANE SHURE, a citizen of the United States, residing at Clarendon, in the county of Donley and State of Texas, have invented certain new and useful Improvements in Clock-Actuated Display Apparatus; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in clock-actuated display signs for displaying scriptural quotations or other reading or display matter and the object in view is to produce a simple and efficient apparatus of this nature so arranged that the matter displayed may be changed at intervals.

The invention consists of a simple and efficient apparatus of this nature having various details of construction, combinations and arrangements of parts which will be hereinafter fully described, shown in the accompanying drawings and then specifically defined in the appended claims.

I illustrate my invention in the accompanying drawings, in which:

Fig. 1 is a front elevation of the apparatus and the dial of a clock.

Fig. 2 is a sectional view on line 2—2 of Fig. 1, looking in the direction of the arrow.

Fig. 3 is a section on line 3—3 of Fig. 2.

Fig. 4 is a sectional view on line 4—4 of Fig. 2, and

Fig. 5 is a sectional view on line 5—5 of Fig. 2.

Reference now being had to the details of the drawings by numerals, 1 designates a clock case having a dial 2, and 3 is an hour hand and 4 the minute hand mounted upon a central shaft 5, to which a gear wheel 6 is fixed, said wheel being in mesh with a pinion 7 which in turn meshes with a gear wheel 8 adapted to make one revolution every twenty-four hours. Fixed to said wheel 8 is a finger 9 projecting beyond

the circumference of the wheel and provided for the purpose which will be presently described.

Mounted upon a shaft 10, shown in Fig. 2 of the drawings, is a reel 11 upon which a tape 12 is wound, and 13 is a hood or shell which fits over said reel and is provided with a slot 14 through which the tape moves. The inner end of said shell is provided with bayonet slots 15 designed to engage the pins 16 to hold the shell in place. A pulley 17 is journaled upon a stub shaft 18, carried by the bracket member 19, secured to the casing, and a similar pulley 20 is journaled upon a shaft 21 over which the tape is adapted to pass, and 22 is a window in the casing through which the matter upon the tape may be displayed. A drum 23 has a spindle 24 at one end, journaled in a bracket member 25 and its other end is journaled in the wall of the casing, as shown in Fig. 3 of the drawings. A circular series of spurs, 26, 75 spaced apart, project from the circumference of said drum and are adapted to engage the tape 12 which latter causes the drum to rotate as the tape unwinds from the reel 11. Said drum 23 has a flange 27 at one end upon a raised portion of which are the series of curved gear teeth 28. Said disk also has a stop 29 fastened to the face thereof and cooperates with a lug 30 projecting from the rotatable tilting lever 31 to stop the reel 23 after having made a complete revolution. The lever 31 has a gear wheel 32 fixed thereto and which is adapted to mesh with the teeth 28 to cause the lever 31 to make a single revolution at each rotary movement of the flange 27. Said lever 31 is journaled in a central aperture formed in the diamond-outlined member 33, the outline of which is shown in dotted lines in Fig. 1, in edge view 95 in Fig. 3 and top plan in Fig. 2. A post 34, shown in Fig. 3, is fastened to the bottom of the casing and has two flat springs 35 and 36 secured to its upper end and the free ends of which springs project beyond the top of the post and are adapted to bear frictionally against the opposite faces of the diamond-shaped member 33 for the purpose of returning the member

to its upright position after having been tilted. Said lever 31 has a laterally projecting lug 37 at one end, as shown clearly in Fig. 2 of the drawings, and which is 5 normally in the path of said finger 9.

A reel 39 is journaled in suitable bearings in the casing, as shown in Fig. 5 of the drawings, and about which the tape 12 is adapted to wind and a thumb nut 40 is 10 fixed to the reel 39 and forms means for rotating the same. A coiled spring 41 is fastened at one end to the pin 42 and its other end to the reel 39 and is adapted to be put under tension when the reel 39 is rotated in 15 one direction. By said spring, the tape, when released, it will be noted, will be automatically wound upon the reel 39.

The operation of my invention will be readily understood and is as follows:—At 20 each revolution of the wheel 8, which is adapted to make a revolution every twenty-four hours, the pin 29 thereon will come in contact with the lug 37, causing the same to tilt slightly, as shown in Fig. 3 of the drawings, and which tilting movement of the lever 31 will cause the lug 30 to be raised out of the path of the stop 29 and which will permit the spring connected to the reel 39 to cause the same to rotate and wind the tape 25 thereon. The movement of the tape will cause the drum 23 to rotate and, when the circular series of gear teeth 28 come in contact with the pinion 32, the lever 31 will be given a single revolution which will 30 throw the lug 37 out of the path of the finger 9 and which will permit the wheel 8 to make another revolution. It will be noted that, when the lever 31 is tilted by the finger 9 coming in contact with the lug 37, the spring 35 40 will be put under tension and, after the pinion 32 has passed by the end of the series of teeth 28, said spring 36 will tend to return the member 33 to its vertical position and also tilt back the shaft 31 to its normal horizontal position.

By this mechanism, it will be noted that the apparatus is entirely automatic in its action and, at each revolution of the wheel 8 which in the present instance is adapted to 50 occur once in twenty-four hours by the gear connections shown, different display matter may be shown at the window or sight opening in the casing. It will be understood, however, that the gear connections between 55 the various parts may be changed to cause display matter to be shown at different intervals without in any way departing from the spirit of the invention.

What I claim to be new is:—

60 1. An automatic clock-actuated display apparatus comprising a casing, a spring-pressed rotatable reel, a display tape adapted to wind thereon, a drum about which said tape passes and which latter causes the drum 65 to rotate, clock mechanism and a gear wheel

rotated thereby, a tilting rotatable lever, means upon the wheel for tilting said lever at each revolution, and gear mechanism intermediate said drum and lever for causing the latter to make a single revolution at 70 each rotary movement of the drum.

2. An automatic clock-actuated display apparatus comprising a casing, a spring-pressed, rotatable reel, a display tape adapted to wind thereon, a drum about which said tape passes and which latter causes the drum to rotate, clock mechanism and a gear wheel rotated thereby, a tilting rotatable lever, means upon the wheel for tilting said lever, at each revolution, gear mechanism intermediate said drum and lever for causing the latter to make a single revolution at each rotary movement of the drum, and means for returning the lever to its normal position after having been tilted. 75 80 85

3. An automatic clock-actuated display apparatus comprising a casing, a spring-pressed, rotatable reel, a display tape adapted to wind thereon, a drum about which said tape passes and which latter causes the drum to rotate, clock mechanism and a gear wheel rotated thereby, a tilting rotatable lever, means upon the wheel for tilting said lever at each revolution, gear mechanism intermediate said drum and lever for causing the latter to make a single revolution at each rotary movement of the drum, and stop mechanism upon said lever and drum, co-operating to limit the movement of the drum. 90 95 100

4. An automatic clock-actuated display apparatus comprising a casing, a spring-pressed, rotatable reel, a display tape adapted to wind thereon, a drum about which said tape passes, gear teeth upon said drum, clock mechanism and a gear wheel rotated thereby, a finger projecting from said wheel, a tilting rotatable lever having a lateral extension in the path of said finger, a gear wheel fixed to the lever and adapted to engage the teeth upon said drum, and means for returning the lever to its normal position after having been tilted. 105 110

5. An automatic clock-actuated display apparatus comprising a casing, a spring-pressed, rotatable reel, a display tape adapted to wind thereon, a drum about which said tape passes, gear teeth upon said drum, clock mechanism and a gear wheel rotated thereby, a finger projecting from said wheel, a tilting rotatable lever having a lateral extension in the path of said finger, a gear wheel fixed to the lever and adapted to engage the teeth upon said drum, a member in which said lever is pivoted, and springs bearing 115 120 125 against the opposite faces of said member.

6. An automatic clock-actuated display apparatus comprising a casing and clock mechanism and gear wheel actuated thereby, a finger projecting from said wheel, a 130

spring-pressed rotatable reel, a tape secured to and adapted to wind upon the reel, a rotatable drum, a disk at the end of the drum and gear teeth upon the disk, a reel from 5 which the tape unwinds, a tilting rotatable lever and mounting therefor, one end of said lever having a lug in the path of said finger and a pinion at the other end adapted to engage said teeth upon the disk, a stop upon

the disk, and a lug projecting from the lever 10 adapted to engage said stop.

In testimony whereof I hereunto affix my signature in presence of two witnesses.

RALPH DEANE SHURE.
